J. C. ANDEREGG

FASTENER

Original Filed June 26, 1926

UNITED STATES PATENT OFFICE.

JOSEPH C. ANDEREGG, OF ALGOMA, WISCONSIN.

FASTENER.

Application filed June 26, 1926, Serial No. 118,820. Renewed March 31, 1928.

This invention relates to certain improvements in fasteners and it is an object of the invention to provide a fastener for an opening comprising a plurality of interlocking members under control of a slide.

Another object of the invention is to provide a fastener wherein a plurality of members are disposed in alternate assembly along the marginal portions of an opening to be closed, said members being effectively maintained in interlocking engagement through the medium of an associated slide upon movement of such slide in one direction.

The invention consists in the details of construction and in the combination and arrangement of the several parts of my improved fastener whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a fragmentary view in elevation illustrating a fastener constructed in accordance with an embodiment of my invention and in applied position and partly in interlocking assembly;

Figure 2 is a fragmentary sectional view taken longitudinally through certain of the adjacent members of the fastener as herein disclosed;

Figure 3 is a view in top plan of the structure as illustrated in Figure 2;

Figure 4 is a view in top plan of one of the members comprised in the fastener as herein set forth.

As disclosed in the accompanying drawing, A denotes a shoe upper or the like provided with a conventional central opening 1. My improved fastener coacting with the marginal portions of said upper A or the like defines such opening 1.

My improved fastener comprises a plurality of members M suitably secured to the marginal portions of the upper A defining the opening 1 and extending alternately in opposite directions inwardly of such opening 1. Each of the members M comprises a

shank 2 suitably affixed to the upper A and a portion 4 extending beyond a margin of the upper to interlock with oppositely fixed members M. The lower face of the portion 4 is inclined downwardly and terminates in a rounded portion or lower extremity 3. The end face 5 of the portion 4 is inclined upwardly and inwardly from the lower extremity 3.

The upper face of the portion 4 is provided with an open recess 7 of a curvature in cross section substantially similar to the cross sectional curvature of the rounded portion or lower extremity 3 and which is adapted, when the opposite members are in interlocking connection, to receive the rounded portion or lower extremity 3 of the portion 4 of the adjacent member M as is believed to be clearly illustrated in Figure 1.

Coacting with the assembled members M is a slide S of any desired construction but preferably of the type illustrated in my application for patent executed on even date herewith. When the slide S is moved in one direction, the members M are caused to disengage or separate, but when the slide is moved in the opposite direction, the adjacent members M are caused to effectually interlock and thereby substantially close or tie the marginal portions of the upper A defining the opening 1.

The marginal portions of the upper A defining the opening 1, as herein disclosed, are provided with the suitably positioned stop members 8 whereby the locking movement of the slide S is limited.

As is particularly illustrated in Figure 1, it is to be noted that the marginal portions of the upper A defining the opening 1 are also provided therealong with the reinforcing strips 9 and in order to compensate for such strips to assure the proper placement of the members M, it is to be noted in Figure 4 that the shank 2 of each member is bifurcated, as at 10, to straddle a reinforced marginal portion with the outer extremities of the resultant arms of the shank 2 inwardly disposed, as at 11, whereby the shank is effectively clinched behind the reinforcement.

From the foregoing description it is thought to be obvious that a fastener constructed in accordance with my invention is particularly well adapted for use by rea-

son of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. An opening and closing device comprising a plurality of interlocking members carried by the parts to be opened and closed, each of said members including a shank secured to one of the parts, and a portion extending beyond the margin of such part, said extended portion having a lower face inclined downwardly and terminating in a rounded lower extremity, the end face of said extended portion being inclined upwardly and inwardly from the lower extremity, the top face of the extended portion being provided with an open recess of a curvature in cross section similar to the cross sectional curvature of the rounded extremity, the lower extremity of the extended portion of one member seating in the open recess of an opposite member when said members are in interlocking engagement, and a slide movable along the parts to be opened and closed, said slide engaging the interlocking mem-

bers to separate and unlock the same, or to move said members into interlocking engagement.

2. An opening and closing device comprising a plurality of interlocking members carried by the parts to be opened and closed, each of said members including a shank secured to one of the parts, and a portion extending beyond the margin of such part, said extended portion having a lower face inclined downwardly and terminating in a rounded lower extremity, the end face of said extended portion being inclined upwardly and inwardly from the lower extremity, the top face of the extended portion being provided with an open recess of a curvature in cross section similar to the cross sectional curvature of the rounded extremity, the lower extremity of the extended portion of one member seating in the open recess of an opposite member when said members are in interlocking engagement, and a slide movable along the parts to be opened and closed, said slide engaging the interlocking members to separate and unlock the same, or to move said members into interlocking engagement, the shank of each of the members being bifurcated and straddling a marginal portion of one of the parts.

In testimony whereof I hereunto affix my signature.

JOSEPH C. ANDEREGG.
